CONTROLLER FOR MACHINES

Edward Vossen, Brooklyn, N. Y., assignor to Stop-Motion Devices Corp., Brooklyn, N. Y., a corporation of New York

Application December 27, 1943, Serial No. 515,737

12 Claims. (Cl. 66—157)

This invention relates to new and useful improvements in controllers for machines, and particularly refers to controllers for knitting machines.

It is customary to provide a knitting machine with stop motion switches which close electric circuits for energizing a controller to stop the knitting machine when certain undesirable contingencies arise, such as knots coming along upon the yarn or thread, or the yarn or thread breaking, or a press-off or hole appearing in the knitted material. This invention proposes certain improvements in said controller.

The invention contemplates associating a signal lamp with the controller in such a manner that the operator is informed whether the controller is "on" or "off." It is proposed that the controller be provided with a housing and that the signal lamp be mounted within the housing and be viewable through a window opening therein.

The invention also relates to improved mechanism of the controller. It is proposed to provide the controller with a keeper element connected with an armature and cooperative with a bolt-like member in a certain fashion for latching the controller in an "on" position, and to provide means for electrically releasing the controller so that it may assume an "off" position.

The invention proposes certain means for urging the bolt-like member to an "off" position and for moving the bolt-like member to an "on" position, when and as desired.

Another object of the invention resides in the provision of a novel circuit for controlling the signal lamp and a certain electro-magnet of the controller.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front elevational view of a controller constructed in accordance with this invention.

Fig. 2 is a plan view of Fig. 1.

Fig. 3 is a fragmentary front elevational view similar to Fig. 1 but showing the controller with the front cover of the housing removed.

Fig. 4 is a vertical sectional view taken on the line 4—4 of Fig. 3.

Fig. 5 is a vertical sectional view taken on the line 5—5 of Fig. 3.

Fig. 6 is a bottom sectional view taken on the line 6—6 of Fig. 3.

Fig. 7 is a fragmentary view similar to Fig. 3 but showing the controller in an "on" position.

Fig. 8 is a vertical sectional view taken on the line 8—8 of Fig. 7.

Fig. 9 is a fragmentary enlarged sectional view taken on the line 9—9 of Fig. 1.

Fig. 10 is a fragmentary vertical sectional view taken on the line 10—10 of Fig. 1.

Fig. 11 is a fragmentary elevational view looking in the direction of the line 11—11 of Fig. 10.

Fig. 12 is a schematic wiring diagram of the device.

15 The controller, in accordance with this invention, includes a housing 15 of box-like construction provided with several lugs 16 by which it may be attached on a suitable support. The housing 15 is also provided with a removable cover 17.

20 A controller shaft 18 is turnably mounted on and through opposed walls of said housing 15 and is adapted to be manually turned to an "on" position. The shaft 18 is provided with a handle 19 by which it may be readily turned. It is also provided with a crank arm 20 for connection with suitable linkage intended to be connected with the knitting or other machine to stop same when the controller shaft 18 turns to its "off" position.

25 Resilient means in the nature of a relatively strong spring 21 is coaxially mounted on the controller shaft 18 for normally urging it into an "off" position. The spring 21 has one of its ends 22 engaged through an opening in one of the walls for the housing 15 and has its other end 30 engaged in an opening in a collar 23 fixedly mounted on the controller shaft 18. A stop collar 24 is fixedly mounted on the controller shaft 18 and is adapted to strike one of the walls for the housing 15 for limiting turning of the controller shaft 18 to its "off" position. More particularly, the collar 24 is located near one of the walls of the housing 15 and is of a larger diameter than the distance from its center to said wall of the housing. A portion of the collar 35 24 is cut away forming a flat side 25 which permits the shaft 18 to be turned to an "on" position.

40 In Fig. 4 one end of the flat side 25 is shown engaging the adjacent wall of the housing 15 which limits turning of the controller shaft 18 to its said "off" position.

45 An armature 26 is movably mounted within the housing 15. The armature 26 is in the nature of a flat plate of magnetic material horizontally disposed. Its back end portion is provided with pins 27 pivotally mounted in lugs 28 of an elec-

50 55

tro-magnet support bracket 29. This bracket 29 is mounted on a support member 30 which is mounted upon the back wall of the housing 15. A finger 31 projects from the support bracket 29 and extends across the top of the armature 26 for limiting upward pivoting of said armature.

An electro-magnet 32 is mounted on the electro-magnet support bracket 29 and is located directly beneath the armature 26 for attracting said armature. A spring 33 is mounted upon the bottom face of the armature 26, and acts against the electro-magnet 32 for normally urging the armature 26 upwards against said finger 31. This position of the armature 26 must be considered as its initial position. The armature 26 has one of its ends laterally extended and formed into a keeper element 34. The latching position of the keeper element 34 is the position it is in when the armature 26 is in its said initial position.

A bolt-like member 35 is movably mounted in the housing 15 and is in an "on" position when engaged and held by said keeper element 34, which is then in its latching position. This bolt-like member 35 has a radially extending hook portion 36 which is cooperative with the keeper element 34. This hook portion 36 extends from a base portion 37 which is pivotally mounted. A pivot pin 38 mounted on one wall of the housing 15 pivotally connects with one end of the base portion 37 and the other end of said base portion is provided with a pivot 39 which is supported by a bracket 40 attached to the housing 15.

The bolt-like member 35 is normally urged to an "off" position when said controller shaft 18 is in an "off" position by a stud 41 which is mounted on a collar 42 fixedly mounted on the controller shaft 18. This stud 41 engages against a radially projecting finger 43 projecting from the base portion 37 of said bolt-like member 35. A spring 44 normally urges the bolt-like member 35 into its "on" position. This spring 44 has one end attached to the base portion 37 and has its other end attached to a clip 45 mounted upon the back wall of the housing 15. The spring 44 tends to turn the bolt-like member 35 counter-clockwise, as viewed in Fig. 4. However, the stud 41 engaging the finger 43 of the bolt-like member 35 opposes the action of the spring 44.

A stop 46 is mounted on the back wall of the housing 15 and is adapted to stop the motion of the finger 43 when the bolt-like member 35 is turning counter-clockwise under the action of the spring 44 and the hook portion 36 reaches and is engaged with the keeper element 34, see Fig. 8. The hook portion 36 has a beveled face 47 adapted to cam down the keeper element 34 as the bolt-like member 35 reaches its "on" position, so that the keeper element 34 when released moves up behind the beveled face 47 (see particularly Figs. 4 and 8) to latch the bolt-like member 35 in its "on" position. It should be noted that in the "on" position of the controller shaft 18, and in the "on" position of the bolt-like member 35, as illustrated in Fig. 8, the stud 41 has completely moved off of the finger 43 so that the spring 44 would be free to turn the bolt-like member 35 a further distance counter-clockwise, except for the fact that the finger 43 is now engaging the stop 46. It should also be noted that the bolt-like member 35 in Fig. 8 is caught by and held by the keeper element 34 from turning clockwise and that the stud 41 indirectly holds the controller shaft 18 from

turning counter-clockwise because it is jammed against the base portion of the finger 43. This action holds the controller shaft 18 in its "on" position until such time that the keeper element 34 drops the hook portion 36 of the bolt-like member 35.

A signal lamp 50 is mounted within the housing 15. This signal lamp is mounted on a conventional socket having a clip 51 frictionally clipped upon a support prong 52 attached to the back wall of the housing 15. The signal lamp 50 is located immediately back of an aperture 53 formed in the cover 17. A lens 54 is mounted in and closes the aperture 53. A normally open switch is mounted within the housing 15 and comprises an insulation block 55 mounted upon one of the walls of the housing 15 and supporting a stationary contact 56 and a normally spaced spring contact 57. An insulation pin 58 projects from the collar 23 and in the "on" position of the controller shaft 18 strikes against and bends the spring contact 57 so that its engages the stationary contact 56, closing said switch. An electric circuit 59 connects the electric lamp 50 and switch 56, 57 in series so that when the controller shaft 18 is in its "on" position the lamp 50 will be lighted. The circuit 59 is connected up with a pair of binding posts 60, 61 mounted on, but insulated from the housing 15. These binding posts are connected up with an electric supply circuit 62.

A second electric circuit 63 connects with the supply circuit 62 and with the electro-magnet 32, and a controlling switch 64, 65. This controlling switch is in the nature of a leaf spring 64 supported on but insulated from a bracket 66 attached to the electro-magnet support bracket 29. A contact 65 is mounted upon the hook portion 36 of the bolt-like member 35 and is cooperative with and electrically engages the spring contact 64 when the bolt-like member 35 is in its "on" position. The contact 65 is connected with the ground 67 which in this case results from the fact that the contact 65 is not insulated from but is electrically connected with the hook portion 36 of the bolt-like member 35. Said second circuit 63 may be traced from the ground 67, shown in Fig. 12, to the ground 67' of a stop motion device 70. This stop motion device 70 is of the type generally used on knitting machines to detect when a thread or yarn breaks, or when a knot in the thread or yarn approaches the needles of the knitting machine. The stop motion device 70 may be of any design and construction which closes said second electric circuit 63 in the emergencies mentioned, or other emergencies.

The details of the stop motion device 70 will not be given in this specification as it forms no part of this invention and devices of this type are generally known.

The armature 26 may be manually moved from its initial position by push button means which is characterized by a push button 71 mounted through an aperture 72 in the cover 17. The push button 71 is held in a forward position by one arm 73 of a bell crank having another arm 74 located directly over the armature 26. The bell crank 73, 74 at the junction of its arms is provided with a loop portion 75 cut from the material of the arms thereof. A staple 76 passes through the loop portion 75 for pivotally supporting the bell crank 73, 74. A spring 77 is supported by the staple 76 and acts against the arm 73 for normally holding the

push button 71 forwards. When the push button 71 is pushed inwards the bell crank 73, 74 will be pivoted so that the arm 74 thereof moves the armature 26 downwards and thus out of its initial position. This action will move the keeper element 34 so that said keeper element drops the bolt-like member 35. This causes the controller to function to turn the controller shaft 18 to its "off" position.

The operation of the controller for knitting and other machines, is as follows:

In Figs. 1-6 the controller is illustrated in its "off" position. It may be turned on by manually moving the handle 19 for turning the controller shaft 18 clockwise, as illustrated in Fig. 4, so that the collar 42 and the stud 41 carried by said collar are correspondingly turned. The stud 41 will move along the finger 43 of the bolt-like member 35 so that the spring 44 will pivot the bolt-like member 35 counter-clockwise as illustrated in Fig. 4 until it reaches its "on" position in which the beveled face 47 will cam past the keeper element 34 to reach the position illustrated in Figs. 7 and 8. The stud 41 moved until it reached the base of the finger 43, as illustrated in Fig. 8. In this position of the finger 43, said finger forms a stop for preventing the stud 41 from moving back to its original position, and thus the controller shaft 18 is indirectly latched in its "on" position.

In the "on" position of the controller the insulation pin 58 engages the spring contact 57, closing the switch 56, 57 which closes the electric circuit 59 causing the lamp 50 to be illuminated. In the "on" position of the controller the contact 65 engages the spring contact 64, closing the switch 64, 65 which controls the electro-magnet 32. However, no current is being supplied to said electro-magnet because the circuit 63 is held open by the stop motion device 70. Only when the stop motion device 70 functions to close the circuit 63 will the electro-magnet 32 become energized. It then draws the armature 26 against the holding action of the spring 33 so that the armature 26 is moved from its initial position. The keeper element 34 is moved downwards from its latching position, freeing the bolt-like member 35. The controller shaft 18 is now free to turn to its "off" position. The bolt-like member 35 will be moved to its "off" position indirectly by the spring 22. The switch 64, 65 is now open, which opens the circuit 63 so that electric current is not wasted even though the stop motion device 70 now closes said circuit 63.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a controller for machines, a housing, a controller shaft turnably mounted on said housing to be manually turned to an "on" position, resilient means for turning said shaft to an "off" position, a signal lamp for the controller, a normally open switch, an electric circuit for lighting said lamp and controlled by said switch, and an arm connected with said shaft for holding said switch closed in the "on" position of said shaft.

2. In a controller for machines, a housing, a controller shaft turnably mounted on said housing to be manually turned to an "on" position,

resilient means for turning said shaft to an "off" position, a signal lamp for the controller, a normally open switch, an electric circuit for lighting said lamp and controlled by said switch, and an arm connected with said shaft for holding said switch closed in the "on" position of said shaft, said signal lamp being mounted within said housing, and said housing having a window opening through which the light from the signal lamp may be seen.

3. In a controller for machines, a housing, a controller shaft turnably mounted on said housing to be manually turned to an "on" position, resilient means for turning said shaft to an "off" position, a signal lamp for the controller, a normally open switch, an electric circuit for lighting said lamp and controlled by said switch, and an arm connected with said shaft for holding said switch closed in the "on" position of said shaft, said normally open switch comprising a stationary contact and a movable contact cooperative with said stationary contact, and said arm being adapted to move said movable contact to close said switch.

4. In a controller for machines, a housing, a controller shaft turnably mounted on said housing to be manually turned to an "on" position, resilient means for turning said shaft to an "off" position, an electric magnet mounted in said housing, a movably mounted armature for said electro-magnet, resilient means for urging said armature to an initial position, a keeper element connected with said armature and located in a latching position when said armature is in said initial position, a bolt-like member movably mounted in said housing and in an "on" position when engaging and held by said keeper element in its latching position, and means connected with said shaft for urging said bolt-like member to an "off" position when said shaft is in an "off" position and for moving said bolt-like member to an "on" position engaged and held by said keeper when said shaft is turned to its "on" position and holding said shaft on its "on" position as long as said bolt-like member is in its "on" position.

5. In a controller for machines, a housing, a controller shaft turnably mounted on said housing to be manually turned to an "on" position, resilient means for turning said shaft to an "off" position, an electric magnet mounted in said housing, a movably mounted armature for said electro-magnet, resilient means for urging said armature to an initial position, a keeper element connected with said armature and located in a latching position when said armature is in said initial position, a bolt-like member movably mounted in said housing and in an "on" position when engaging and held by said keeper element in its latching position, and means connected with said shaft for urging said bolt-like member to an "off" position when said shaft is in an "off" position and for moving said bolt-like member to an "on" position engaged and held by said keeper when said shaft is turned to its "on" position and holding said shaft in its "on" position as long as said bolt-like member is in its "on" position, said bolt-like member having a hook portion with a beveled face for camming past said keeper element to an "on" position in front of the keeper element.

6. In a controller for machines, a housing, a controller shaft turnably mounted on said housing to be manually turned to an "on" position, resilient means for turning said shaft to an "off"

position, an electric magnet mounted in said housing, a movably mounted armature for said electro-magnet, resilient means for urging said armature to an initial position, a keeper element connected with said armature and located in a latching position when said armature is in said initial position, a bolt-like member movably mounted in said housing in an "on" position when engaging and held by said keeper element in its latching position, and means connected with said shaft for urging said bolt-like member to an "off" position when said shaft is in an "off" position and for moving said bolt-like member to an "on" position engaged and held by said keeper when said shaft is turned to an "on" position and holding said shaft in its "on" position as long as said bolt-like member is in its "on" position, said bolt-like member having a hook portion with a beveled face for camming past said keeper element to an "on" position in front of the keeper element and said bolt-like member having a base portion pivotally mounted within said housing.

7. In a controller for machines, a housing, a controller shaft turnably mounted on said housing to be manually turned to an "on" position, resilient means for turning said shaft to an "off" position, an electric magnet mounted in said housing, a movably mounted armature for said electro-magnet, resilient means for urging said armature to an initial position, a keeper element connected with said armature and located in a latching position when said armature is in said initial position, a bolt-like member movably mounted in said housing and in an "on" position when engaging and held by said keeper element in its latching position, and means connected with said shaft for urging said bolt-like member to an "off" position when said shaft is in an "off" position and for moving said bolt-like member to an "on" position engaged and held by said keeper when said shaft is turned to its "on" position and holding said shaft in its "on" position as long as said bolt-like member is in its "on" position, and including resilient means urging said bolt-like member to its "off" position, a stud connected with said controller shaft, a finger connected with said bolt-like member and engaging said stud due to the resilient action of said resilient means urging said bolt-like member to its "off" position.

8. In a controller for machines, a housing, a controller shaft turnably mounted on said housing to be manually turned to an "on" position, resilient means for turning said shaft to an "off" position, an electric magnet mounted in said housing, a movably mounted armature for said electro-magnet, resilient means for urging said armature to an initial position, a keeper element connected with said armature and located in a latching position when said armature is in said initial position, a bolt-like member movably mounted in said housing and in an "on" position when engaging and held by said keeper element in its latching position, and means connected with said shaft for urging said bolt-like member to an "off" position when said shaft is in an "off" position and for moving said bolt-like member to an "on" position engaged and held by said keeper when said shaft is turned to its "on" position and holding said shaft in its "on" position as long as said bolt-like member is in its "on" position, and including resilient means urging said bolt-like member to its "off" position, a stud connected with said controller shaft, a

finger connected with said bolt-like member and engaging said stud due to the resilient action of said resilient means urging said bolt-like member to its "off" position, and a stop for limiting motion of said bolt-like member to its "on" position.

9. In a controller for machines, a housing, a controller shaft turnably mounted on said housing to be manually turned to an "on" position, 10 resilient means for turning said shaft to an "off" position, an electric magnet mounted in said housing, a movably mounted armature for said electro-magnet, resilient means for urging said armature to an initial position, a keeper element 15 connected with said armature and located in a latching position when said armature is in said initial position, a bolt-like member movably mounted in said housing and in an "on" position when engaging and held by said keeper element in its latching position, and means connected with said shaft for urging said bolt-like member to an "off" position when said shaft is in an "off" position and for moving said bolt-like member to an "on" position engaged and held by said keeper when said shaft is turned to its "on" position and holding said shaft in its "on" position as long as said bolt-like member is in its "on" position, and including resilient means urging said bolt-like member to its "off" position, 30 35 a stud connected with said controller shaft, a finger connected with said bolt-like member and engaging said stud due to the resilient action of said resilient means urging said bolt-like member to its "off" position, and a stop for limiting motion of said bolt-like member to its "on" position, said finger having a base portion engaging and holding said stud when said controller shaft is in its "on" position.
10. In a controller for machines, a housing, a 40 controller shaft turnably mounted on said housing to be manually turned to an "on" position, resilient means for turning said shaft to an "off" position, an electric magnet mounted in said housing, a movably mounted armature for said electro-magnet, resilient means for urging said armature to an initial position, a keeper element 45 connected with said armature and located in a latching position when said armature is in said initial position, a bolt-like member movably mounted in said housing and in an "on" position when engaging and held by said keeper element in its latching position, and means connected with said shaft for urging said bolt-like member to an "off" position when said shaft is in an "off" position and for moving said bolt-like member to an "on" position engaged, and push button means for manually moving said armature from its initial position.
11. In a controller for machines, a housing, a 60 controller shaft turnably mounted on said housing to be manually turned to an "on" position, resilient means for turning said shaft to an "off" position, an electric magnet mounted in said housing, a movably mounted armature for said electro-magnet, resilient means for urging said armature to an initial position, a keeper element 65 connected with said armature and located in a latching position when said armature is in said initial position, a bolt-like member movably mounted in said housing and in an "on" position when engaging and held by said keeper element in its latching position, and means connected with said shaft for urging said bolt-like member to an "off" position when said shaft is in an "off" position and for moving said bolt-like member to an "on" position engaged, and push button means for manually moving said armature from its initial position.
- 70
- 75

member to an "on" position engaged, and push button means for manually moving said armature from its initial position, comprising a push button mounted through a portion of said housing, a bell crank pivotally mounted on said housing and having one arm extended across the back of the push button and its other arm extended across said armature, and resilient means urging said bell crank to push said push button forwards.

12. A controller for machines, comprising a housing, a controller shaft turnably mounted on said housing to be manually turned to an "on" position, resilient means for turning said shaft to an "off" position, a movably mounted armature for an electro-magnet, resilient means for urging said armature to an initial position, a keeper element connected with said armature and located in a latching position when said armature is in said initial position, a bolt-like member movably mounted in said housing and in an "on" position when engaging and held by said keeper element in its latching position, means connected

with said shaft for urging said bolt-like member to an "off" position when said shaft is in an "off" position and for moving said bolt-like member to an "on" position engaged and held by said keeper when said shaft is turned to its "on" position and holding said shaft in its "on" position as long as said bolt-like member is in its "on" position, an electro-magnet for moving said armature from its initial position, a signal lamp for said controller, a normally open switch, means connected with said shaft for holding said switch closed in the "on" position of said shaft, an electric circuit for lighting said lamp and controlled by said switch, a second electric circuit for energizing said electromagnet, a stop motion switch device for normally keeping said second electric circuit open until activated, a switch for controlling said second electric circuit, and means for closing said latter switch when said shaft is in its "on" position and opening said latter switch when said shaft is in its "off" position.

EDWARD VOSSEN.
